JOSE LEANDRO MONTALVO GUENARD, OF PONCE, PORTO RICO

CLOSURE

Application filed November 30, 1928. Serial No. 322,725.

This invention relates to closures and particularly to closures and closure structures especially adapted for use in connection with bottles, jars, or similar fluid receptacles.

Among the objects of the present invention is to provide a closure and closure structure which is simple in construction and operation and readily suited to economic manufacture.

Another object of the present invention is to provide a closure adapted for substantially permanent association with a receptacle and hingedly associated therewith, whereby it may be moved upwardly from closing position to permit discharge of the material within the receptacle.

A further object of the present invention is to provide a closure of the type described which may be readily associated with the receptacle after the usual shipping closure has been removed therefrom, or it may be permanently secured by wire or the like, to the receptacle instead of the usual shipping closure.

Another object of the invention is to provide a closure supporting structure whereby the closure may be retained in sealing position with respect to the receptacle and whereby releasing from such position will automatically cause the closure to assume a position free from interference with the discharge of material from the receptacle.

Other objects of the invention include the combination and interrelation of parts whereby the whole forms a convenient readily attachable and detachable simple structure, and as the closure is retained in combination with the receptacle, contamination of the closure is prevented when sterile liquids are used and thus the device is particularly adapted for medical use, and an easily locked closure is obtained by simple downward pressure on the knob thereof.

With these and other objects of the present invention in view, reference may be had to the accompanying drawings, in which

Figure 1 is a perspective view of one form of my present invention;

Fig. 2 is a vertical sectional view of that form of the invention illustrated in Fig. 1;

Fig. 3 is a top plan view of the closure base as will be hereinafter described;

Fig. 4 is a side elevation of the base illustrated in Fig. 3, and

Fig. 5 is a detail perspective view of a sealing bushing adapted for association with said base.

Referring more particularly to the drawings, the preferred embodiment of my invention herein illustrated, includes a base 10 illustrated in detail in Figs. 3 and 4. The base includes an elongated horizontally positioned transversely extending member 11 depending from which there is provided a tubular sleeve 12 crimped through the aperture 13 of the member 11, and is adapted to be surrounded by a sealing bushing 13, as illustrated in Fig. 5, which is preferably formed of cork, rubber, or other suitable semi-flexible material. The tubular portion or sleeve 12 and the bushing 13 are adapted to be received within the neck of a receptacle, which has been illustrated in the form of a bottle 14. The tubular portion 12 and bushing 13 are removably secured within the neck 15 of the bottle and sealed relatively thereto through the bushing 13, which through its expansive character, retains the base thereon.

Associated with one extremity of the member 11, a spring closure supporting member 15 is provided, hingedly associated therewith as indicated at 16. The member 15 is preferably formed of spring metal, such as steel or the like, and is bowed upwardly, the free end being adapted for engagement with the free end of the member 11, as indicated at 17. The removable engagement of the free end of the bowed member 15 with the extremity of the member 11 is provided for by an inwardly turned portion 18 thereof with which is associated a finger manipulating extremity 19. The central portion of the bowed member 15 is centrally apertured as at 20 as shown in Fig. 2, to receive therethrough a threaded member 21, the head of which is positioned downwardly and engages a washer 22 through the medium of which a compressible stopper 23 is engaged in association with the threaded member 21 and the bowed member 15. The upper end of the threaded

member 21 is provided with a knob 24, preferably formed of heavy metallic material, the knob being secured in association with the bowed member 15 and the threaded member 21 by the provision of a threaded retainer 25 associated with the member 21, or the knob 24 may be threaded to accomplish the purpose of the retainer 25.

The stopper 23 is preferably formed of cork, rubber, or other suitable compressible material, whereby the member may be forced into tight engagement with the upper portion of the tubular member 12 of the base 10, and thus prevent the flow of liquid therethrough. The stopper 23 is covered by a metallic cap 26 which will hold the stopper 23 with the member 21. The heavy characteristic of the knob 24 is adapted to control the position of the bowed member 15 when the stopper is out of engagement with the tubular portion of the base 10. The arrangement is such that the center of gravity of the bowed member 15 is outward from the hinged portion 16 thereof after slight upward movement of the knob 24. Thus after disengagement of the portion 18 from the point 17, the bowed member 15 will pivot about the hinge 16 and assume the position indicated in dotted lines in Fig. 2.

The springy characteristic of the bowed member 15 and the configuration thereof with respect to the portion 11, is such that for engagement of the portion 18 at 17, downward flexing of the bowed member 15 is necessary. Thus the stopper 23 is retained within the tubular portion 12, and upon releasing the catch portion 18, a reflexing action of the bowed member 15 takes place, thus urging the removal of the stopper 23 from the tubular portion 12 and throwing the bowed member 15 backwardly, whereby the center of gravity will be outward from the hinged portion 16, as hereinbefore described, whereby the bowed member and its associated stopper and knob assume the position indicated by the dotted lines in Fig. 2. Locked closure of the device is accomplished by simple downward movement of the knob 24 and pressure thereon.

From the foregoing it will be readily seen that my present invention provides an improved automatically operable bottle stopper which may be readily associated with various kinds and configurations of receptacles without clamping means or extra securing devices.

It will be readily understood that the invention as herein disclosed may undergo various changes and modifications and the full use of equivalents be resorted to without departing from the spirit or scope of the appended claims.

What is claimed is:

1. In a closure for receptacles, the combination with a receptacle-engaging element;

of a transversely extending base carried thereby, and a closure member pivotally associated with one end of said base and engageable with the opposite end of said base, said member having a flexible arm and a closure plug carried by said arm. 70

2. In a closure for receptacles, a receptacle-engaging element including a transversely-extending base, a flexible closure-carrying member pivotally attached to one end of said base, said closure-carrying member having a catch at its free end adapted to engage the corresponding free end of said base thereby retaining said closure-carrying member in a flexed position on said base. 75

3. In a closure for receptacles, a receptacle-engaging element including a transversely-extending base provided with a longitudinal depression to form a spout, a flexible member pivotally attached to one end of said base, a stopper element centrally secured to said flexible member at one side thereof, a weighted manipulating element centrally secured to said flexible member at the other side thereof, a catch formed by the free end of said flexible member and being integral therewith for engaging the free end of said base to provide for automatic pivotal movement of said flexible member with respect to said base upon disengagement of the free end of said base and said flexible member. 80

Signed at New York in the county of New York and state of New York this 27th day of November A. D. 1928.

JOSÉ LEANDRO MONTALVO GUENARD.
